[57] ABSTRACT

A strand brake assembly for preventing excessive sag in a messenger strand during installation of the strand on supporting poles. The assembly includes a base plate having a strand guide and a brake member cooperating therewith to brake the strand against retrograde movement. The base plate is attached to another plate member which is adapted to be clamped between the clamp plates of a standard strand clamp, spacing the clamp plates apart a distance sufficient to allow a messenger strand to be slidably received within the strand groove defined by portions of the clamp plates. In one embodiment of the invention, the base plate is pivotally attached to the other plate member to provide automatic alignment of the cable guide with a strand passing through the guide and the strand groove of the clamp.

9 Claims, 5 Drawing Figures

STRAND BRAKE ASSEMBLY

BACKGROUND OF THE INVENTION

In stringing coaxial cable, conventional practice is to lash the cable to a messenger strand extending between adjacent supporting poles. While cable installation can frequently be accomplished by suspending cables from an existing messenger strand, in many instances it is necessary to first install the supporting messenger strand.

When pulling a new messenger strand into place, the strand is trained through strand grooves in clamps mounted on each of the poles. During the strand pulling operation the opposing clamp plates of the clamps are not tightened into clamping engagement with the strand but instead, the plates are bolted together loosely enough to allow the strand to slide through the strand groove defined by the opposing plates.

One serious problem encountered during the installation of a messenger stand as described above, is that the weight of the strand, which can be substantial, will cause the strand to sag between poles unless it is clamped at each pole. This is generally unacceptable, since sagging strands will cause blockage of streets, highways and the like over which the strand is passing, and is completely intolerable at railroad crossings. Additionally, a strand left sagging between poles any length of time is quite likely to attract children who may be injured by swinging on the strand or cause damage to the strand itself. It will also be apparent that a strand swinging in a high wind can arc up onto high voltage lines.

There are a number of cable and rope gripping devices in the prior art, such as those shown in U.S. Pat. Nos. 1,898,677; 3,204,309; and 3,364,529, some of which are designed for stringing conductors. However, the conventional way of preventing sagging of the messenger strand during the pulling operation is to station a man on the pole at the strand clamp where, acting in coordination with the other members of the stringing crew, he alternately tightens and loosens the clamp at which he is positioned.

While this is obviously an undesirable situation in that it requires the full time services of a lineman positioned on the pole and requires a relatively high degree of coordination between the members of the stringing crew, this approach has nonetheless been an accepted one since it is a time tested approach to preventing sag during the pulling operation.

SUMMARY OF THE INVENTION

The present invention provides a strand brake assembly which is mounted on the supporting poles and provides a braking action against retrograde movement of the messenger strand, and consequently, strand sag, during the strand pulling operation.

The strand brake includes a clamp engageable portion adapted to be clamped between the opposing clamp plates of a pole mounted strand clamp. Attached to the clamp engageable portion of the plate is a base plate, carrying a strand guide and a brake which cooperates with the strand guide and permits movement of the strand through the brake in only the pulling direction.

The clamp engageable portion of the brake is provided with an opening or openings, which receive the bolt or bolts of the pole mounted strand clamp. When

in use with a conventional three bolt clamp, the clamp engageable portion of the brake is provided with three openings, which are formed conveniently as notches to facilitate installation and removal of the strand brake.

- 5 The clamp engageable portion of the brake is of sufficient thickness that, when clamped between the opposing clamp plates it spaces the clamp plates far enough apart to allow the strand being installed to slide within the strand groove defined between the clamp plates.
- 10 The strand guide mounted on the base plate is positioned such that the strand lies in substantially the same plane as it passes through the strand guide and the strand groove.

While the base plate may be rigidly fixed to the clamp engageable portion of the brake, in a preferred embodiment of the invention the base plate is pivotally attached to the clamp engageable portion for pivotal movement about an axis extending normal to the plane in which the strand lies. In this way, the strand guide is 15 self-aligning, positioning itself automatically to accommodate divergencies from a straight line pull into the strand clamp.

As will be apparent from the following description, the present invention provides a strand brake assembly 20 which includes a strand brake of relatively simple and inexpensive construction which can be attached readily to a conventional pole mounted clamp to provide a brake assembly which prevents effectively sagging of the messenger strand during pulling operations.

30 BRIEF DESCRIPTION OF THE DRAWINGS

FIG. 1 is a perspective view showing generally, the installation of a messenger strand;

FIG. 2 is a perspective view of a pivotal strand brake 35 in accordance with the present invention;

FIG. 3 is a perspective view of a strand brake installed in a pole mounted clamp;

FIG. 4 is a cross-sectional view through a pole, clamp and strand brake; and

40 FIG. 5 is an elevational view of a fixed strand brake.

45 DESCRIPTION OF THE PREFERRED EMBODIMENTS

As seen in FIG. 1 of the drawings, in a typical strand pulling operation the strand 10 is unreeled from the reel stand 12 and trained over a block 14 at a first pole 15 and thence through partially opened strand clamps 16 on succeeding poles 17. A conventional strand clamp, as best seen in FIGS. 3 and 4, will include a pair of opposed clamp plates 18 and 20 one of which is provided with a relieved portion 22 to define with the other clamp plate, a strand groove.

The two plates may be mounted on a pole 17 by means of a through bolt 24 provided with washers 26 55 on opposite sides of the pole and a nut 28 which secures the bolt in the pole. The bolt is provided with a second nut 30 which clamps the clamp plates 18 and 20 together with the strand 10 fixed in the strand groove between the two plates. Usually, additional nuts and bolts 32, 34 are utilized to secure the clamp plates together.

In conventional strand pulling operations the nuts 30 and 34 are backed off enough to allow the cable 10 to 60 slide within the strand groove. As a result, a man must be stationed on the pole at the strand clamp to alternately tighten and loosen the nuts to prevent sag between poles.

With the strand brake assembly of the present invention, however, sag between poles is eliminated automatically without the necessity of positioning a lineman on the pole to actuate manually the strand clamp. Thus, as best seen in FIGS. 2 and 3 of the drawings, a strand brake 40 is provided which includes a clamp engageable portion 42 and a base plate 44.

The clamp engageable portion 42 is provided with openings in the form of notches 46, 48 and 50 along its lower edge which are adapted to slide over the bolts 24 and 32 between the clamp plates 18 and 20. The nuts 30 and 34 are then tightened, clamping the portion 42 therebetween and spacing the plates 18 and 20 far enough apart to allow a strand 10 received within the strand groove to slide freely.

The base plate 44 may be pivotally attached, as at 52, to the portion 42 for pivoting movement about an axis substantially normal to the plane in which the strand lies as it passes through the strand brake assembly. A brake lever 54 is pivotally mounted on the base plate 20 at 56 and carries a brake shoe 58 having a strand engaging portion 60.

A strand guide 62 is also mounted on the base plate and has a strand engaging and supporting surface 64 cooperating with the surface 60 on the brake shoe to grip a strand therebetween. The brake member is spring loaded into strand gripping relationship with the strand guide by means of a spring 66, and a stop 68 projects from the base plate and is engaged by the brake lever 54 when the brake member is in gripping relationship with the strand guide 62. Stop pin 68 also prevents complete or partial unwinding of the spring by stopping the lever 54. The user is thus prevented from unwinding spring 66 by operating the lever 54 in the wrong direction during loading.

With this construction, and as best seen in FIG. 3 of the drawings, a strand 10 is trained through the strand brake 40 and the strand clamp in the direction indicated by the arrow in FIG. 3. The pivotal attachment of the base plate to the portion 42 allows the strand guide to align itself automatically to accommodate any divergency in the approach of the strand to the strand clamp.

The strand 10 is free to move between the opposed surfaces of the brake shoe and the strand guide and through the strand groove in the strand clamp in the direction indicated by the arrow. However, retrograde movement of the strand in the opposite direction is resisted by the strand brake, thereby automatically preventing sagging of the messenger.

While the pivotal brake described above will usually be preferable in that it provides automatic alignment of the strand guide, where alignment is not a problem the relatively simpler construction shown in FIG. 5 of the drawings may be utilized. Thus, as seen in FIG. 5 of the drawings, the strand brake 70 includes a clamp engageable portion 72 to which is fixed a base plate 74.

The portion 72 is provided with openings in the form of notches 76, 78 and 80 to receive the bolts 24 and 32 of the strand clamp. The cable guide in this version may consist of simply a plate 82 fixed to and projecting from the base plate 74 and having a cable engaging and supporting surface 84. A brake member consisting of a lever 86 and a shoe 88 is pivotally mounted on the base plate at 90 and the strand engaging surface 92 of the shoe 88 is urged toward the surface 84 by means of a spring 94.

5 A pin 96 is welded to the plate 74 and serves as a stop, similarly to stop pin 68. Aside from the differences in construction between the previously described embodiment and that shown in FIG. 5 of the drawings, the strand brake 70 is attached to the strand clamp 16 and functions similarly to the strand brake 40.

In both embodiments it will be noted that the brake assembly of the present invention provides a relatively simple, inexpensive mechanism for preventing sag during messenger strand pulling operations.

10 While the forms of apparatus herein described constitute preferred embodiments of the invention, it is to be understood that the invention is not limited to these precise forms of apparatus, and that changes may be made therein without departing from the scope of the invention.

15 What is claimed is:

1. A strand brake assembly comprising:
  - a. a clamp engageable portion,
  - b. a strand clamp including opposed clamp plates,
  - c. means clamping said clamp engageable portion between said clamp plates,
  - d. a base plate attached to and projecting from said clamp engageable portion,
  - e. a strand guide mounted on said base plate and including at least one strand engaging and supporting surface,
  - f. a brake member pivotally mounted on said base plate for gripping in cooperation with said strand guide surface a strand disposed therebetween, and
  - g. means urging said brake member into strand gripping relationship to said strand guide surface.
2. The assembly of claim 1 further comprising:
  - a. stop means projecting from said base plate, engageable by said brake member when in said strand gripping relationship to said strand guide surface and preventing rotation of said lever past a preselected point.
3. The assembly of claim 1 wherein said brake member comprises:
  - a. a lever pivotally mounted on said base plate, and
  - b. a brake shoe mounted on said lever and having a strand engaging surface opposing said surface of said strand guide.
4. The assembly of claim 1 wherein:
  - a. said base plate is pivotally attached to said clamp engageable portion for pivotal movement about an axis substantially normal to a strand supported by said strand guide.
5. The assembly of claim 1 wherein:
  - a. said base plate is fixedly attached to said clamp engageable portion.
6. The assembly of claim 1 wherein:
  - a. said clamping means comprises bolts extending through said clamp plates, and
  - b. said clamp engageable portion has openings therein receiving said bolts.
7. The assembly of claim 6 wherein:
  - a. said openings in said clamp engageable portion comprises notches.
8. The assembly of claim 1 wherein:
  - a. said clamp plates have portions defining a strand groove therebetween, and
  - b. said strand groove is positioned to support a strand therein in substantially the same plane as said strand guide.
9. The assembly of claim 8 wherein:
  - a. said clamp engageable portion received between said clamp plates spaces said clamp plates sufficiently to allow a strand to be retained in but slideable in said strand groove.
